UNITED STATES PATENT OFFICE

ARTHUR THOMAS, OF THORNTON HEATH, ENGLAND, ASSIGNOR TO THE ACCOUNTING & TABULATING CORPORATION OF GREAT BRITAIN, LIMITED, OF LONDON, ENGLAND

RIBBON FEEDING MECHANISM

Application filed March 8, 1928. Serial No. 260,099.

This invention relates to ribbon-feed mechanism for typewriters, adding machines and the like and more particularly for tabulating printing machines of the power-driven type.

5 In such a specific application, a large number of printing members may be operated at each stroke with the machine running at 70 or 80 strokes per minute; constant reversals of the direction of running of the ribbon are thus necessary while owing to the length of 10 ribbon in use, which may amount for example to 18 inches, it is of importance that the ribbon should be driven at a uniform tension to prevent looping or sagging.

15 With the object of providing a ribbon feed mechanism suitable for the purposes indicated, the present invention consists in the combinations of parts hereinafter set forth and particularly pointed out in the claims.

20 An illustrative form of the invention will now be described with reference to the accompanying drawings, in which:—

Figure 1 is a front elevation;

Figure 2 an end elevation;

25 Figure 3 is a plan partly in section on the line III—III of Figure 2, as seen from below;

Figure 4 is a plan of the ribbon spools, while

30 Figures 5 and 6 are sections on the lines V—V and VI—VI respectively of Figure 3.

In carrying the invention into effect according to the form shown by way of example, the bed-plate, 1, of the machine is 35 provided with a number of uprights, 2, carrying brackets, 4, 5, in which the vertical spindles 6, 7, are mounted, their upper ends passing through thimbles, 8, 9, respectively, which rest upon the brackets, 4, 5. These 40 thimbles have upper flanges, 8a, 9a, and lower flanges, 8b, 9b, the latter being provided with flats (see 8c, in relation to the thimble, 8, in Figure 2) which co-operate with any convenient adjacent part of the frame of the

45 machine to prevent turning. In addition the thimbles are pressed upwards by springs, 8d, 9d, against the ribbon spools, 10, 11, mounted respectively on the spindles, 6, 7. As the spools rotate, a frictional drag is thus created 50 by their contact with the upper flanges, 8a,

9a, of the thimbles and a steady tension maintained on the ribbon. The ribbon, 12, wound on these spools, is carried round guide pins or rollers, 14, and supported in suitable guides, 15, which hold it in the correct position in front of the paper platen, 17, round which the paper, 18, is passed. The spindles, 6, 7, are provided at their lower ends below the bed-plate, 1, with bevel gears, 20, 21, engaging with corresponding bevel gears, 22, 23, mounted upon the shafts, 24, 25, the bevel gears, 22, 23, being oppositely-disposed in relation to the bevel gears, 20, 21, so that for the same direction of rotation of the shafts, 24, 25, the spindles, 6, 7, rotate in opposite 65 directions. Each spool, 10 and 11, is provided with a pin, 30, attached to an arm, 31, pivotally mounted at 32, on the upper flange, 33, of the spool, the pin, 30, passing through slots, 34, in both the upper and lower flanges 70 of the spool below the latter of which it projects. The centre hub, 35, of the spool is provided with a recess into which the pin, 30, fits when the ribbon is wound on the spool. The ribbon, 12, the end of which is attached 75 to the pin, 30, will when unwound from the spool pull the pin, 30, from its recess so that it makes contact with a bell-crank lever, 36, one arm, 36a, of which has a turned-over portion, 36b, as shown on the right-hand side of Figure 4. The other arm, 36c, of the bell-crank lever, 36, is connected by the link, 37, to a connecting rod, 40, which is pivoted to a collar, 41, mounted on the first-motion shaft, 42, this shaft being rotated backwards and forwards through a small arc by any suitable mechanism such as the lever, 42a, connecting-rod, 42b, and crank-disc, 42c, continuously rotated from any convenient source of power. The lever, 40, is kept in its upper position as 90 shown in Figure 2 by means of a spring, 43, the link, 37, continually swinging backwards and forwards owing to the movements of the shaft, 42.

Below the link, 37, a lever, 44, is mounted 95 upon the upper end of the short vertical shaft, 45, rotatable in a suitable bushing, 46, in the bed-plate, 1, of the machine. The lower end of the shaft, 45, is provided with a lever, 47, which engages between two collars, 100

48, 49, on the horizontal shaft, 50. When the pin, 30, is pulled over by the ribbon so that it strikes the bell-crank lever, 36, the link, 37, will be depressed and its lower end will engage the lever, 44, pulling it over and sliding the reversing shaft, 50, longitudinally by means of the lever, 47.

A reversing mechanism as described is associated with each reel or spool.

10 The shaft, 42, is provided with a cam, 53, which co-acts with a roller, 54, on the end of a lever, 55, pivoted at the point, 56. In rigid relation to the lever, 55, is another lever, 57, the end of which is connected by a spring, 58, secured to the frame of the machine at 59, thus keeping the roller, 54, in engagement with the cam, 53. The lever, 55, is provided with a depending projection, 61, which engages with a stop, 62, on the catch, 63, which can be slid up and down vertically by any suitable means not shown. When the catch, 63, is raised, the stop, 62, makes contact with the projection, 61, and the lever, 55, is held in its highest position so that the oscillating movement of the shaft, 42, and cam, 53, impart no motion thereto, the chain of elements forming the drive being thereby broken.

The lever, 55, is connected by the link, 70, to a lever, 71, mounted upon the shaft, 72, which is pivoted in the bracket plate, 73, 74, on the bed-plate, 1. On the shaft, 72, is also mounted another lever, 75, the end of which is provided with a roller, 76, which engages in a slot, 77, in the flange, 78, of the sleeve, 79. The flange, 78, also carries a pawl, 80, which engages with the ratchet wheel, 82, loosely mounted upon the juxtaposed ends of the shafts, 24, 25.

40 Mounted upon the bracket plate, 74, is a pawl, 83, held in engagement with the teeth on the pinion, 82, by means of the spring, 84, so as to prevent rearward rotation or rebound of the pinion. The pinion, 82, is connected on either side by dog couplings to the two members, 90, 91, which are freely rotatable on the shafts, 24, 25, and are provided with teeth, 92, 93, rounded off on their outer corners as shown in Figure 3. The sleeve, 79, is freely rotatable on the member, 91 and the pinion, 82.

The collars, 94, 95, are secured rigidly to the shafts, 24, 25, and maintain the two toothed members, 90, 91 in engagement with the pinion, 82. The two collars are provided with slots, 96, 97, respectively, in which slide two keys, 98, 99, mounted respectively on sleeves, 100, 101, slideable on the shafts, 24, 25, the sleeves being provided with circumferential grooves, 102, 103, into which fit levers, 104, 105, mounted on the reversing shaft 50. The keys, 98, 99, have turned down ends, 106, 107 which fit loosely into recesses in the members, 100, 101, the keys as a whole being held in position by means of garter

springs, 108, 109, situated in circumferential grooves in the sleeves, 100, 101. The sleeves, 100, 101, and keys, 98, 99, carried by them thus form a pair of clutch members movable simultaneously by the shaft 50, and so disposed that one clutch member is withdrawn before the other is inserted.

When the shaft, 50, is moved longitudinally from one position to another, one or other of the keys, 98, 99, will engage with the teeth, 92 or 93, if in exact alignment with the slots, 96 or 97, in the collars, or if not in such alignment when the shaft is moved, the keys will first be tilted by the radius on the members, 90, 91, and then be pressed by the springs, 108, 109, between the teeth, 92, 93, as they come into line.

The operation of the form of mechanism described is as follows:

Supposing the ribbon is moving from left to right in Figure 1, the reversing shaft, 50, will be in its left-hand position as seen in Figure 3, the key, 99, engaging with the toothed member, 91, while the key 98, is disengaged from the toothed member, 92; the drive is then effected from the first-motion shaft, 42, by way of the cam, 53, which oscillates the lever, 55, and by means of the link, 70, transmits such oscillations to the lever, 71, shaft, 72, and lever, 75, thereby in turn rocking the flange, 78, of the sleeve, 79, and at each reciprocation moving the ratchet wheel, 82, and toothed members, 91, 92, through one ratchet tooth. This part of the driving mechanism operates continuously and forms part of the means for driving the spools which is common to both. From the toothed members, 91, 92, the remainder of the drive is individual to the particular spool being driven. Thus, in the present instance the toothed member, 91, and the key, 99, transmit the movement through the collar, 95, to the shaft, 25, and thence through the bevel wheels, 23, 21, and vertical spindle, 7, to the right-hand spool. Finally, when as described the ribbon is entirely unwound from the left-hand spool, 10, its pin, 30, will be pulled by the ribbon into a position such that it engages with the turned-over end of the bell-crank lever, 36, thus lowering the link, 37, so that the latter, which is inoperative during winding, though continuously oscillated by the connecting rod, 40, will engage with the lever, 44, and turn the short vertical shaft, 45, (which is stationary during winding) and thereby the reversing shaft, 50, will be moved by the lever, 47, to the right as shown in Figure 3, disengaging the key, 99, and engaging the key, 98, the drive now proceeding by way of the shaft, 24, and vertical spindle, 6. The ribbon is then wound on the left-hand spool, 10, and unwound from the right-hand spool until on completion of the operation the pin, 30, of the right-hand spool will be pulled out by the tension of the

ribbon and again reverse the drive. The ribbon thus performs only the very light work of lowering the link, 37, the actual clutching and declutching being performed by power, while in addition due to the nature of the drive, the ribbon feed and the clutch reversing are carried out at different times, since, when the link, 37, is lowered to engage with the lever, 44, movement of the lever, 5 42a, in one direction to feed the ribbon is necessarily followed immediately by a movement in the opposite direction which acts to change over the clutches but does not feed the ribbon; the clutch reversing is therefore 10 effected at a moment when the ribbon is stationary and not subjected to driving tension.

Although one specific form of mechanism by way of illustrating the invention has been described in detail, it will be obvious to those skilled in the art that subordinate components or groups of components of the complete mechanism may take other forms, and I desire that the claims appendant hereto may be given as broad an interpretation as the 20 law allows.

Having now described my invention, what I claim as new and desire to secure by Letters Patent is:—

1. In a ribbon feed, the combination of a 30 pair of ribbon spools; a first-motion shaft; means for driving one of said spools to wind the ribbon thereon and unwind it from said other spool; means for driving said other spool to wind the ribbon thereon and unwind 35 it from said first-mentioned spool, parts of said driving means, including said first-motion shaft, being common to both said driving means; means for changing over from one of said driving means to the other; 40 means actuated from said first-motion shaft for operating said changing-over means; means for holding said actuating means normally in an inoperative position; and means including a spool-carried member movable 45 under the pull of the ribbon for bringing said actuating means into the operative position.

2. In a ribbon feed the combination of a 50 pair of ribbon spools; means for driving said spools, said driving means having a drive common to both spools and a drive individual to each spool and included in said common drive, a first-motion shaft having an oscillating movement, a cam mounted on said shaft, a lever oscillated by said cam and means for holding said lever in an inoperative position in relation to said cam: together with automatic means brought into operation by the tension of the ribbon for alternately 55 bringing one of said individual drives into operative relation to said common drive and rendering inoperative the other of said individual drives.

3. In a ribbon feed, the combination of a 60 65 pair of ribbon spools; means for driving said

spools, said driving means having a drive common to both spools and a drive individual to each spool; together with automatic means brought into operation by the tension of the ribbon for alternately bringing one of said individual drives into operative relation to said common drive and rendering inoperative the other of said individual drives, said common drive including a member rotated step-by-step and having two sets of clutch teeth and said automatic means including a pair of clutch members, each with a spring-controlled key to engage said clutch teeth and means for moving said clutch members one into and one out of operative relation to said step-by-step member.

4. In a ribbon feed, the combination of a 70 pair of ribbon spools; means for driving said spools, said driving means having a drive common to both spools and a drive individual to each spool; automatic means brought into operation by the tension of the ribbon for alternately bringing one of said individual drives into operative relation to said common drive and rendering inoperative the other of 75 said individual drives, said automatic means including a train of mechanism, part of which is stationary during winding and part continuously oscillated but in an inoperative position during winding; together with means responsive to the movement of a spool-carried member under the pull of the ribbon for bringing said continuously-oscillated part from its inoperative position into driving 80 relation with said stationary part.

5. In a ribbon feed, the combination of a 85 pair of ribbon spools; means for driving said spools, said driving means having a drive common to both spools and a drive individual to each spool and included in said common drive a member and means for rotating said member step-by-step; means for preventing rebound of said member and consequent slackening of the ribbon between steps; together with automatic means brought into 90 operation by the tension of the ribbon for alternately bringing one of said individual drives into operative relation to said common drive and rendering inoperative the 95 other of said individual drives.

6. In a ribbon feed, the combination of a 100 pair of ribbon spools; means for driving one of said spools to wind the ribbon thereon and unwind it from the said other spool; means for driving said other spool to wind the ribbon thereon and unwind it from said first-mentioned spool, parts of said driving means, including a power shaft and a reciprocating member receiving its movement therefrom, being common to both said driving means; means for changing over from one of said driving means to the other; and means including a spool-carried member movable under the pull of the ribbon for bringing said 105 changing-over means into operation, said 110

changing-over means and said means for bringing said changing-over means into operation being actuated during different strokes of said reciprocating member.

- 5 7. In a ribbon feed, the combination of a pair of ribbon spools; means for driving one of said spools to wind the ribbon thereon and unwind it from the said other spool; means for driving said other spool to wind the ribbon thereon and unwind it from said first-mentioned spool, parts of said driving means, including a power shaft and a chain of elements operated therefrom, being common to both said driving means; manually-operable
10 means for rendering said chain inoperative at will; power-operated means for changing over from one of said driving means to the other; and means including a spool-carried member movable under the pull of the ribbon for bringing said changing-over means into operation.

In testimony whereof I have signed my name to this specification.

ARTHUR THOMAS.
